TOLBERT LANSTON, OF WASHINGTON, DISTRICT OF COLUMBIA.

Letters Patent No. 100,644, dated March 8, 1870.

IMPROVEMENT IN PADLOCKS.

The Schedule referred to in these Letters Patent and making part of the same.

To all whom it may concern:

Be it known that I, TOLBERT LANSTON, of Washington, in the county of Washington, and District of Columbia, have invented a new and valuable Improvement in Padlocks; and I do hereby declare that the following is a full, clear, and exact description of the construction and operation of the same, reference being had to the annexed drawings making a part of this specification, and to the letters and figures of reference marked thereon.

Figure 1, of the drawings, is a representation of my invention with one face removed, to show the internal construction.

Figure 2 is a similar view, the bolt being shot.

Figures 3, 4, 5, 6, 7, and 8 are details.

My invention relates to padlocks, and consists mainly in the construction of the tumblers and wards, and the arrangement of the bolt and pivoted case, designed to form a strong and convenient padlock, simple of construction, and difficult to be picked.

The case A is formed in two parts, pivoted together at the central point by the pin *a*.

The bolt B forms a part of the upper portion of the section C of the case, and is arranged in such a manner that when the lock is unfastened, its upper surface will fill the space left by the parting of the walls of sections C and D of the case.

The triangular spaces made by the parting in the sides of the case above the pivot *a* are closed by thin extensions of the plates forming the sides of the section D, which slide in corresponding depressions in the sides of the section C.

From the upper corners of the case project the rigid jaws *b b*, which meet above the center of the lock, and form the clasp thereof, by means of which it is attached to the staple. A tenon is formed on the end of either jaw, to correspond with a mortise in the other.

When the lock is fastened, by bringing the jaws together, the sections C and D pass below the pivot, and exhibit an angular space between.

The sections of the case are fastened together by a hinge-joint encircling the pin *a*, from which point the walls extend downward until they turn at the bottom to form the curved wall of the case.

The upper edge of the bolt B is curved, corresponding to the bend in the upper portion of the wall of the section D, and is consequently held firmly in position at all times.

It is evident that the bolt cannot be moved upward to unlock. This operation is, therefore, accomplished by drawing the tumblers *H H* downward, until their heads clear the catch of the bolt.

The action of the compressing-spring *e* upon the parted walls of the case below the pivot will cause the lock at once to fly open and drop from the staple, the jaws *b b* unclasping at their central point of junction.

H H designate the tumblers, pressed upward against the bolt by the action of the separate springs *n n*.

and arranged to move independently of each other. They are secured in place by the pins *s* operating in the slots *z z*, and by the staple *G*, mortised upon the tenons in both sides of the section D of the case, or forming a portion of either side, and secured to the other by mortise and tenon.

The pin *t* keeps the tumblers from moving horizontally, and thereby interfering with the action of the bolt.

Between the tumblers are placed the slotted sliding plates *h h*, which serve to keep the tumblers at the proper distance apart.

K designates the inner casing, within which the tumblers slide. It is secured to the side of the case, and provided with a partition, *i*, which divides the tumblers from the wards.

The perpendicular rows of teeth *r r* form the wards. These teeth project horizontally toward the key-hole, and each of them is made similar in shape and size to the teeth *r r* of the tumblers, which project between the teeth of the wards, through the slots *l l* in the partition *i*.

The teeth *r r* have different horizontal positions, and as they are the only means provided for operating the tumblers, the projections *g* on the key must correspond in relative position.

It will readily be perceived that the lock cannot be opened until all the tumblers are drawn down. This arrangement, together with the multiplicity of similar teeth presented, is designed to prevent the lock from being picked.

The pin upon which the key turns is marked *P*.

A small plate, *f*, is pivoted at its base, and operated by a spring, *m*.

When the key is introduced, it passes down between the projections *u u* of this little plate, which, therefore, turns with it in unlocking. But the moment the key is released, after the operation, it is returned by the spring plate to its original position opposite the key-hole, through which it can be at once drawn.

As an additional security against picking, the lower portion of the case *K* may be extended over the springs *n* to the wall of the lock.

What I claim as my invention, and desire to secure by Letters Patent, is—

1. The sectional case herein described, hinged at or near its center, arranged to operate by the spring *e*, and having the jaws *b b* and hook *B*, forming a part thereof, substantially as and for the purposes specified.

2. In combination with the casing *K*, having wards *r r*, the single-acting tumblers *H*, provided with teeth *r*, arranged at different heights, and similar to the teeth *r* of the wards, as specified.

In testimony that I claim the above, I have hereunto subscribed my name in the presence of two witnesses.

Witnesses: TOLBERT LANSTON.
